UNITED STATES PATENT OFFICE.

EARL KEITH LOCKARD, OF SANTA BARBARA, CALIFORNIA.

DESIGN FOR A LAMP-POST.

Application filed April 4, 1928. Serial No. 26,122. Term of patent 7 years.

To all whom it may concern:

Be it known that I, EARL KEITH LOCKARD, a citizen of the United States, residing at Santa Barbara, in the county of Santa Barbara and State of California, have invented a new, original, and ornamental Design for a Lamp Post, of which the following is a specification, reference being had to the accompanying drawing, forming a part thereof.

I claim:

The ornamental design for a lamp post, as shown.

E. KEITH LOCKARD.
